JOHN WARREN BELL, OF BELLINGHAM, WASHINGTON, ASSIGNOR OF ONE-HALF TO
JAMES A. LOGGIE, OF BELLINGHAM, WASHINGTON.

PIPE AND TUBE CLEANER.

1,133,607.

Specification of Letters Patent. Patented Mar. 30, 1915.

Application filed October 12, 1914. Serial No. 866,229.

To all whom it may concern:

Be it known that I, JOHN WARREN BELL, a citizen of Canada, and a subject of His Royal Highness George V of Great Britain, 5 and a resident of 2006 I street, Bellingham, in the county of Whatcom and State of Washington, have invented certain new and useful Improvements in Pipe and Tube Cleaners, of which the following is a specification.

10 My invention relates to improvements in pipe and tube cleaners in which a revolving body or bodies are used to break up and dislodge the scale or other solid accumulations 15 in boiler tubes and other pipes; and the objects of my improvement are to provide a cleaner which can be used in both straight and curved tubes, which will act positively to break up the solid accumulations of scale 20 therein and which will not injure the tubes when doing the work.

I attain these objects by the mechanism 25 illustrated in the accompanying drawing, in which—

Figure 1 is a side elevation of my tube cleaner and Fig. 2 is an end elevation of the same.

Similar characters refer to similar parts 30 in both views. Certain parts of both views are broken into in order to show other parts hidden thereby.

1 is a cutter head adapted for revolution by the flexible shaft 2. This head consists of a hollow truncated cone with its larger 35 end closed and tapered to engage with a screw on the end of flexible shaft 2. The shell of head 1 is pierced by holes, of rectangular cross section. These holes are in pairs, and a center line through each pair of holes in 40 intersects the longitudinal center line of the head and is also an element in the surface of a helix in which the center lines of each of the other pairs of holes also lie. As illustrated, the head contains six pairs of said 45 holes, and in each pair is placed one of the six cutters 3—8. Each cutter is double bitted that is has both ends sharpened. Cutters 3—6 are diamond pointed while the bits of cutters 7 and 8 are rounded. Cutter 50 3 is inserted in the smaller end of the head and is shorter than cutter 8 which is inserted in the larger end of the head. The lengths of cutters 4—7 are graduated between the

lengths of cutters 3 and 8. The cutters are free to move endwise back and forth in said 55 holes to a limited amount, as 3 to positions indicated in dotted outline at 3' and 3'', said movement of each cutter being restricted by stop pins 3^a, 4^a, etc., which are rigidly inserted in holes in said cutters and further 60 serve to prevent the cutters from leaving the head. The length of longest cutter 8 is somewhat less than the diameter of the flues to be cleaned.

In using my cutter it is introduced in the 65 upper end of the tube and caused to revolve. The cutting tools adapt themselves to the varying diameter due to the presence of scale and rout out the same, meanwhile the tapering form in which the revolving bits move 70 together with the helical arrangement of the same induces forward progress of the cutter down a boiler tube. Also since there is no considerable pressure which can operate to hold the cutting bits in close contact with 75 the tube, and also since the cutting bits on the longest cutters are rounded, when the scale has been removed down to the smooth tube surface these bits cannot cut into said tube surface to an injurious extent. 80

Although I prefer to use the tapering form of cutter head as shown, I have done satisfactory work with a cylindrical form of head.

My invention resides in the cutter head 85 with cutters suitable for revolution within the tube and does not concern itself with the particular power means used to revolve the same.

I have done effective and rapid work in 90 completely removing hard and thick scale from within tubes with such a cutter as described coupled to a pipe and revolved by hand. And, although I have illustrated my new tube cleaner head attached to a flexible 95 shaft adapted for revolution by any convenient means, it is also suited for attachment to a water motor or any other source of power which may conveniently serve to produce the necessary rotation in the surroundings and under the conditions where the cleaner must work. 100

Having thus fully described my invention, what I claim to be new and desire to secure by Letters Patent is—

105 In a machine of the character described

the combination with a rotatable cutter head having radial slideways through its body, of normally freely reciprocating double-bitted cutters in said slideways having their 5 bits simultaneously protruding beyond said head, and means to limit the endwise movement of said cutters in said slideways.

Copies of this patent may be obtained for five cents each, by addressing the "Commissioner of Patents, Washington, D. C."

Signed at Bellingham in the county of Whatcom and State of Washington this 3rd day of October A. D. 1914.

JOHN WARREN BELL.
